UNITED STATES PATENT OFFICE.

DIMITRI SENSAUD DE LAVAUD, OF NEW YORK, N. Y.

ROTARY CASTING.

1,323,252.

Specification of Letters Patent.

Patented Dec. 2, 1919.

Application filed March 25, 1919. Serial No. 285,027.

To all whom it may concern:

Be it known that I, DIMITRI SENSAUD DE LAVAUD, a citizen of the United States of Brazil, and a resident of New York, in the 5 county of New York and State of New York, have invented certain new and useful Improvements in Rotary Casting, of which the following is a specification.

This invention relates to rotary or centrifugal casting, and provides an improved method of cooling and rotating the mold-structure and an improved apparatus to facilitate carrying out the process. By the 10 present invention, the problems of providing ball bearings to avoid jamming of the mold-structure in the journaling-structure, such as the ball bearings described in my copending application Serial No. 194,977, of providing arrangements for water cooling the 15 mold-structure under pressure, such as those discussed in my copending application Serial No. 194,976, and of providing power means for rotating the mold-structure other than the cooling fluid, such as the means 20 disclosed in U. S. Letters Patent No. 1,276,038 issued to me, are all absent.

The new method involves rotating the mold-structure about an axis out of the horizontal, by floatingly supporting the mold- 25 structure while rotating the same by the action of a stream of fluid under pressure, preferably water; the stream preferably impinging against the mold-structure below its axis and flowing around the outside of 30 the mold-structure for practically the entire circumference of the latter; the stream also, preferably, being so confined and guided that as it flows around the circumference it is of gradually increasing cross section, with 35 such cross section the result of maintaining the stream at substantially the same width, that is, a width substantially equal to the length of the mold-structure, but with the stream of gradually increasing thickness, as 40 it flows around the mold-structure.

The new apparatus to facilitate carrying out the process includes the combination with the mold-structure, of a structure loosely surrounding the mold-structure, such 45 surrounding structure being provided with a fluid inlet approaching the mold-structure below its axis substantially tangentially, a recess following the curvature of the outer periphery of the mold-structure intermediate the ends of the mold-structure, and a plurality of fluid discharge outlets leading

from said recess one adjacent to each end of the mold. Preferably the discharge outlet includes, at opposite ends of the mold-structure, two annular chambers in the surrounding structure, each chamber having a part overlapping and in open communication with a side of the recess at a point removed from the connection between the recess and the inlet, and the discharge outlet also includes a discharge conduit leading from each of the annular chambers.

The invention also provides a novel arrangement, by which the fluid in the stream for sustaining, rotating and cooling the 50 mold-structure is prevented from leaving the spaces between the mold and surrounding structures, despite the comparatively high velocity of the former, while at the same time the use of gaskets is avoided and 55 the relatively moving parts are almost entirely if not entirely out of contact. These objects are preferably attained by a construction wherein the exterior of the mold-structure and the interior of the surrounding 60 structure, at opposite sides of the recess, are both provided with alternate annular ribs and recesses, with each of several ribs on one part seated in but out of contact with each of several ribs on the other,—although, as 65 will be seen in the structure illustrated, the ribs on the mold-structure forming bounding walls of the recess for confining and guiding the stream are in contact with a spirally curved projection in the surrounding 70 structure.

The invention will be more clearly understood from the following description, when taken in connection with the accompanying drawings showing illustratively apparatus 75 at present preferred.

In this drawing,

Figure 1 is a transverse section of a possible embodiment, taken on the line 1—1 of Fig. 2;

Fig. 2 is partially, as to its upper half, an axial section, and partially, as to its lower half, a side elevation;

Fig. 3 is a fragmentary view, being a section on line 3—3 of Fig. 1;

Fig. 4 is a portion of an axial section of a mold, showing a modification;

Fig. 5 is a section taken on line 5—5 of Fig. 4; and

Fig. 6 is a side elevation showing a further modification.

The apparatus of Figs. 1, 2 and 3 will

first be described; and then its operation, from which a full understanding of the novel process may best be had.

The mold-structure, which in the present case is designed to form a pot casting for making piston rings, includes a main body 4, an auxiliary member 5, and a plurality of annular ribs 6 at opposite ends.

The surrounding structure includes, in addition to its parts for confining and guiding the stream of fluid during admission, during working for floatingly sustaining rotating and cooling the mold-structure, and during discharge, an upper section 7 and a lower section 8, detachably bolted together as indicated at 9. Inside the surrounding structure thereby provided, there is formed a plurality of ribs establishing recesses 10 and 11. These recesses receive the ribs 6 on the mold-structure. It will be noted that the ribs 6 in the recesses 10 are out of contact with the latter. In order that, when desired, the auxiliary member 5 may be readily detached from the main body 4 of the mold-structure, without taking down the surrounding or journaling structure, fixed pins 12 are set in the main body as shown in Fig. 2, and the auxiliary member is apertured to receive these pins so that the auxiliary member may be mounted on the main body as illustrated; the pins being transversely slotted and removable wedge-pieces 13 being relied on to maintain the parts 4 and 5 of the mold-structure in secure engagement during casting. It will be seen that centrifugal force will tend to tighten, rather than to loosen the wedge-pieces 13.

The fluid inlet is formed by providing a pipe 14 screwed into the section 8 of the surrounding structure, by providing a cut-away portion 15 in the bottom of the lower section of the mold-structure, and by setting into this cut-away portion a roof-member 16 and a floor-member 17.

The inner edge of the roof-member 16 is downwardly beveled to conform to the conforming curvatures 18 (Fig. 1) inside the surrounding structure which establish a recess 19 of gradually increasing cross section for the sustaining, rotating and cooling stream for the mold-structure. This recess 19 curves around the mold-structure for practically its entire circumference, continuing, beyond the point 20 (Figs. 1 and 3), as a vertically arranged compartment 21 at the inlet side of the mold-structure depending below the axis of the mold-structure. The side bounding walls of this recess 19 are formed by the inner sides of the innermost ribs 6 (Fig. 2) on the mold-structure, which rest lightly against the outer sides of the projections within the two sections of the mold-structure forming the curved walls 18 of the recess 19.

The fluid discharge outlet includes those

parts of the recesses 11 which at any instant are overlapping and in open communication with the bottom of the compartment 21, and the two depending conduits 22 at the bottom of such recesses.

70

Operation.

The stream of water or other suitable fluid, entering the pipe 14, passes through the same and between the roof-members 16 and the floor-member 17, and thence enters the recess 19. As the stream passes around such recess, the mold-structure is floatingly supported, rotated at the requisite speed, and cooled under pressure; the stream being delivered to the recesses 11 and thence to the discharge conduits 22. The paths of the stream, from its entrance into until its discharge from the apparatus, may be followed by noting first the arrows in Fig. 1, then those in Fig. 3, and then those in Fig. 2. The arrangement provided by the ribs 6 and the recesses 10 and 11 prevents escape of fluid from the apparatus, except by way of the discharge conduits, despite the absence of gaskets and the like.

In connection with the parts of the specification here below, reference should be had to Figs. 4, 5 and 6.

The term "mold-structure" is used herein, because while what is practically a unitary mold has been described, it is obvious that a multi-part mold-structure may be used, even a laminated mold-structure as shown in Figs. 5 and 6 and such as described in my copending application Serial No. 264,444. In the case of such laminated mold-structure it would be desirable to place suitable gaskets 23, as of fiber or soft copper, between the different rings or laminæ 24, at the outer marginal edge portions of the latter, to prevent the admission of any fluid into the spaces between the laminæ near the inside of the mold-structure, and it would also be desirable to provide apertures in the laminæ for the passage of tie-bolts 25 therethrough as described in my copending application last identified, but of larger cross sections than the cross sections of the tie-bolts themselves, as indicated at 26, to provide gas-escape passages alongside the tie-bolts lengthwise the mold-structure. In Fig. 4, the thicknesses of the gaskets 23 and consequently of the spaces between the laminæ inside said gaskets, are shown very much exaggerated.

Also, it should be understood that while a comparatively short mold-structure is illustrated, one for making pot castings from which to machine piston rings, the invention can be well applied to a longer mold-structure, as one for making pipe, such a mold-structure, for example, as indicated at 27 in Fig. 6, and in the latter case, one or more surrounding structures 7-8 con-

taining recesses similar to the recesses 19, or equivalent arrangements, can be provided.

I claim—

1. The method of rotating a mold-structure about an axis out of the vertical, in a centrifugal casting apparatus, which consists in floatingly supporting the mold-structure while rotating the same by the action of a stream of fluid under pressure.
2. The method of rotating a mold-structure about an axis out of the vertical, in a centrifugal casting apparatus, which consists in rotating and cooling the mold-structure by confining and directing a stream of fluid under pressure so that such fluid passes into contact with the mold-structure at an angle to the axis of the mold and substantially tangentially to the outer periphery of the mold-structure.
3. The method defined in claim 2, wherein such stream is so confined and directed that it impinges against the mold-structure below its axis.
4. The method defined in claim 3, wherein such stream is so confined and directed after impinging the mold-structure, that the stream flows around the outside of the mold-structure for a portion of its circumference.
5. The method defined in claim 3, wherein such stream is so confined and directed after impinging the mold-structure, that the stream flows around the outside of the mold-structure for more than one-half its circumference.
6. The method defined in claim 3, wherein such stream is so confined and directed after impinging the mold-structure, that the stream flows around the outside of the mold-structure for practically its entire circumference.
7. The method defined in claim 3, wherein such stream is so confined and directed after impinging the mold-structure, that the stream flows around the outside of the mold-structure for a portion of its circumference in a stream of gradually increasing cross-section.
8. In a centrifugal casting machine of the horizontal mold type, the combination with the mold-structure, of a structure loosely surrounding the mold-structure, such surrounding structure being provided with a fluid inlet approaching the mold-structure below its axis substantially tangentially, a recess following the curvature of the outer periphery of the mold-structure intermediate the ends of the mold-structure, and a fluid discharge outlet leading from said recess.
9. In a centrifugal casting machine of the horizontal mold type, the combination with the mold-structure, of a structure loosely surrounding the mold-structure, such surrounding structure being provided with a fluid inlet approaching the mold-structure

below its axis substantially tangentially, a recess following the curvature of the outer periphery of the mold-structure intermediate the ends of the mold-structure, and a plurality of fluid discharge outlets leading from said recess, one adjacent to each end of the mold-structure.

10. The apparatus defined in claim 8, wherein said recess is of gradually increasing cross-section from fluid inlet to fluid outlet.

11. The apparatus defined in claim 8, wherein said recess is of substantially the same width but of increasing thickness from the fluid inlet to the fluid outlet.

12. The apparatus defined in claim 8, wherein the exterior of the mold-structure and the interior of said surrounding structure, at one side of the recess, are both provided with alternate annular ribs and recesses, with a rib on one part seated in a recess on the other, to prevent discharge of the fluid except by way of the outlet while avoiding the use of gaskets between the mold-structure and the surrounding structure.

13. The apparatus defined in claim 9, wherein the exterior of the mold-structure and the interior of the surrounding structure, at opposite sides of the recess, are both provided with alternate annular ribs and recesses, with a rib on one part seated in a recess on the other, to prevent discharge of the fluid except by way of the outlet while avoiding the use of gaskets between the mold-structure and the surrounding structure.

14. The apparatus defined in claim 8, wherein the discharge outlet includes an annular chamber in the surrounding structure having a part overlapping and in open communication with the recess at a point removed from the connection between the recess and the inlet and also includes a discharge conduit leading from the chamber.

15. In a centrifugal casting machine of the horizontal mold type, the combination with the mold-structure, of a structure formed and arranged to include journaling means for the mold and to confine a cooling liquid and maintain said liquid in contact with the exterior of the mold-structure during rotation, the exterior of the mold-structure and the interior of the last mentioned structure being provided with a rib and a recess, with the rib on one structure seated in the recess on the other, to prevent discharge of the liquid between said two structures while avoiding the use of gaskets between such structures.

Signed at New York, in the county of New York and State of New York.

DIMITRI SENSAUD DE LAVAUD.
